 10 Claims. (Cl. 248—201)

In a French Patent No. 1,334,964, entitled "Improved Burner Mounting" there has been described a device for pivotally mounting a burner about a horizontal hinge axis with a view to facilitating the inspection and repairs thereof as well as a quick removal of the burner assembly in relation to the front face of a generator for its replacement or inspection under the best possible conditions. This mounting consisted essentially in providing a hinge having a horizontal axis which permitted the downward pivoting of the burner, this hinge being designed in the fashion of an open support so that the burner could be removed by simply lifting same.

The present invention is directed to the same subject matter as the aforementioned French patent, but the means utilized therefor are still more efficient and simple and ensure a considerable freedom of movement of the burner, notably when it is desired to move it to positions or inclinations permitting an easy access to the different component elements to be checked, repaired or replaced. Moreover, the same means also facilitate the movements of the burner when it is desired to remove same completely in relation to the front face of the generator.

The mounting constituting the subject-matter of this invention is characterized mainly in that it comprises:

At least one burner-supporting bracket secured to the front of the generator;

A track provided on this support;

Rollers mounted on the burner and engaging the track; Stop or locking means for holding the rollers against movement at a predetermined point along the track, and,

If desired, stop means for limiting the inclination of the burner in relation to its support, this movement to the predetermined inclined position resulting from the combination of two movements of the burner in relation to the front of the generator, that is, a movement of translation and a movement of rotation wherein the bearing and fulcrum points are the aforesaid track-engaging rollers.

According to a particularly advantageous embodiment of the invention, the mounting comprises two supports in the form of vertical brackets disposed on either side of the burner, the burner being adapted to rock between the brackets when it is moved to the desired inclined position, the brackets comprising at their upper portion a track bounded by front and rear stops and adapted to receive two pairs of rollers mounted on the lower portion of the burner and disposed on either side thereof.

According to a specific feature of this embodiment the stops limiting the stroke of the rollers at the end of the track are so disposed that they act at the same time as hinge means for one or the other set of rollers carried by the burner.

According to another feature of this typical embodiment, the aforesaid rollers are so positioned in relation to the burner body that the latter is constantly in a condition of stable equilibrium irrespective of the positions of the burner relative to its support.

Other features and advantages of the invention will appear as the following description proceeds with reference to the accompanying drawing illustrating diagrammatically by way of example a typical embodiment of the invention. In the drawing:

FIG. 1 is a diagrammatical side-elevational view show-

2

ing a burner mounted on the front wall of a generator in its operative position;

FIGS. 2, 3 and 4 are diagrammatic views similar to FIG. 1 which show three different inclined positions of the burner in relation to its support.

In the embodiment shown in FIG. 1 the reference numeral 1 designates generally the burner provided with a handle 2, the front wall of a generator chamber adapted for mounting the burner being designated by the reference numeral 3. In the figures, 4 is the front end of a nozzle, 5 a burner mouth projecting into the generator chamber through an aperture (notches) in wall 3, 6 a regulator unit and 7 an ignition transformer. It is clear that with known hinge mountings it is not possible to extract the burner mouth to a limited extent from the interior of the generator, the case being stopped after a relatively short pivoting movement. On the other hand, with known pivotal mountings there is practically no direct access to the regulator 6 and the transformer 7 in the general manner shown in FIG. 3. Finally, none of the constructions proposed up to now permits simultaneously such a convenient accessibility as shown in FIGS. 2 and 4 while allowing the burner to recede sufficiently from the front wall 3 of the generator.

The essential principle of the invention lies in the fact that, to provide the advantages broadly set forth hereinabove and the different desired positions, the combination of two movements, i.e., a movement of translation and a movement of rotation, is utilized in the handling of the burner.

To this end, the burner comprises on its lower portion two pairs of like-sized rollers 8, 9 disposed on either side of the vertical plane of symmetry of the burner, these rollers respectively engaging a pair of lateral supports 10 (only one shown), constituting a pair of vertical brackets secured on the front wall 3 of the generator and flanking the transformer 7. The two supports 10, consisting for example of pressed ribbed sheet-metal elements of substantial thickness, are formed at their upper edges with tracks 11 (one shown) engageable by the pairs of rollers 8 and 9 (only one of each being illustrated). Advantageously, the tracks 11 can be slightly inclined toward the front wall of the generator, so that the nozzles shown at 4 are directed slightly downwards, this arrangement facilitating the flow of fuel thereto under all operative conditions. The sloping of the tracks also tends to maintain the front rollers 9 in positive engagement with the hook-shaped stops 12.

In the specific embodiment illustrated the tracks 11 are provided at their front end with hinge-forming stops 12 and at their rear end with hinge-forming stops 13, only one each of the pairs of stops 12 and 13 on the symmetrically disposed supports 10 are illustrated. The separation of the roller pairs 8 and 9 is substantially less than the spacing between the front and rear stops 12, 13.

In the operative position the burner normally engages the front wall 3 of the generator, owing to the inclination of the tracks, and to the provision, if necessary, of some device for locking the burner in relation to its supports. This locking device may be of any suitable and known type and adapted to be released by means of a trigger pivoted on the handle 2 so that it can be actuated as the handle is gripped for rocking the burner assembly. If desired, this release action may be attended by the operation of switch means for disconnecting the burner from its source of electric current, in order to avoid short circuits and protect the operator entrusted with the inspection or removal of one or more component elements of the apparatus. In this operative position the pair of rollers 9 engage the hinge-forming front stops 12 at the forward end of the track, as shown in FIG. 1.

When the burner is stopped and the operator wishes to inspect the burner head, he may first release the trigger-controlled locking device and then pull the burner assembly backwards by applying thereto a movement of translation in order to extract the burner mouth 5 from the generator and thus cause the pair of rollers 8 to engage the hinge-forming rear stops 13. A subsequent rotation of the burner assembly in the counter-clockwise direction about the horizontal axis of the rear rollers 8 will then bring the assembly to the position illustrated in FIG. 2. Fixed stop means such as an abutment 14, provided in the vertical brackets 10 directly underneath the rear stop 13, will limit the angular movement of the burner to a suitable position sufficient to permit a proper inspection of the burner head. The stops 13, being hook-shaped, have formations 13' which overlie the rollers 8 (or 9) to prevent their lifting off the tracks 11 during the pivoting of the burner.

It will be noted that in the case illustrated in FIGS. 1 and 2 of the drawing the vertical line coincident with the center of gravity 15 is so positioned that in either case the burner assembly is in a condition of stable equilibrium. Thus, the center of gravity 15, whose normal location is intermediate the roller pairs 8 and 9, swings past the rear rollers 8 as the burner is pivoted into the position of FIG. 2.

However, it is also possible as shown in FIGS. 3 and 4, after the burner assembly has been moved through only a part of its backward movement of translation, to lift this assembly slightly from the rear (i.e. to swing it clockwise) and to free the rollers 8 from the rear hinge-forming stops 13. Under these conditions, and if the movement of translation is thereupon continued to the rear, the rollers 9 will engage the rear hinge-forming stops 13. Having thus completed its stroke, the burner assembly can be rotated in the clockwise and the counter-clockwise direction to the positions shown in FIGS. 3 and 4, respectively. It will be noted that in the two cases illustrated in these figures the stop 14 acts likewise as a means for limiting the inclination of the burner assembly, on being engaged by a surface 1' formed by a bottom edge of the burner body, and a vertical plane passing through the center of gravity 15 proves that in either case the burner has a stable position, this center having swung past the front roller 9 in the position of FIG. 3.

The different positions obtainable with the burner mounting according to this invention permits a full access to the regulation devices (relays, transformers, motors, connections, etc.) and to the combustion head (ignition and nozzle).

Of course, it would not constitute a departure from the spirit and scope of the present invention to bring various modifications and alterations to the embodiment shown and described herein; thus, notably the design of the supports 10 may be modified by substituting therefore, for example, lateral rails or races carried by interfitting flanges or the like. Similarly, the two supports may be replaced by a single support consisting either of a lower intermediate rail or of an upper central rail. Besides, curvilinear tracks may be substituted for the rectilinear ones illustrated, to provide variable positions of the guide rollers during the movements of translation and rotation. Thus, for example, the roller-engaged tracks may consist of parallel-edged slots or like elongated apertures formed in flat sections of general curvilinear configuration, suitable stop means being provided thereon for holding the rollers in said apertures or slots against motion in the desired and proper positions. In this case, the number of pairs of rollers may be greater than two.

Besides, the fixed stops 14 for limiting the rocking movement of the burner assembly may be dispensed with, so that the assembly may be rocked to the maximum extent in the clockwise and counter-clockwise directions.

Furthermore, the supports 10 may be extended ver-

tically to constitute a protective casing enclosing the greater portion of the burner assembly.

On the other hand, although in the embodiment illustrated the supports 2 are secured on the front wall 3 of the combustion chamber of a generator, it would not constitute a departure from the principles of this invention to provide supports secured directly in the underlying ground or floor.

Finally, the position of the handle 2 is arbitrary, for it could as well be secured in any other position on the burner assembly, for example in a horizontal plane instead of a vertical plane.

What I claim is:

1. In a generator having an apertured wall for receiving the mouth of an externally positioned burner, the combination with said burner of a mounting therefor including support means adjacent said wall forming at least two substantially horizontal tracks, front and rear stop means rising from at least one of said tracks at locations relatively close to and relatively remote from said wall, respectively; front and rear roller means on said burner normally resting on said tracks for stably supporting said burner thereon, said front and rear stop means being more widely separated than said front and rear roller means and being respectively engageable by the latter in an operative position in which the burner mouth projects through said wall and an inoperative position in which the burner mouth is withdrawn from said wall; and a formation on said support means above said one of said tracks overlying only said rear roller means in said inoperative position while leaving said front roller means freely movable in an upward direction, thereby enabling pivotal movement of said burner on said rear roller means upon the latter contacting said rear stop means and said formation.

2. The combination defined in claim 1 wherein said rear stop means comprises a hook-shaped projection on said support means, said formation being part of said projection.

3. The combination defined in claim 1 wherein said front roller means is of substantially the same size as said rear roller means and engageable by said rear stop means upon a lifting of said rear roller means from said tracks and subsequent rearward displacement of said burner.

4. In a generator having an apertured wall for receiving the mouth of an externally positioned burner, the combination with said burner of a mounting therefor including support means adjacent said wall forming at least two substantially horizontal tracks; front and rear stop means rising from at least one of said tracks at locations relatively close to and relatively remote from said wall, respectively; front and rear roller means on said burner normally resting on said tracks for stably supporting said burner thereon, said front and rear stop means being more widely separated than said front and rear roller means and being respectively engageable by the latter in an operative position in which the burner mouth projects through said wall and an inoperative position in which the burner mouth is withdrawn from said wall; a formation on said support means above said one of said tracks overlying only said rear roller means in said inoperative position while leaving said front roller means freely movable in an upward direction, thereby enabling pivotal movement of said burner on said rear roller means upon the latter contacting said rear stop means and said formation; and abutment means on said support means below said tracks, said burner having a surface engageable with said abutment means in at least one limiting position of said pivotal movement.

5. The combination defined in claim 4 wherein said front roller means is of substantially the same size as said rear roller means and engageable by said rear stop means upon a lifting of said rear roller means from said tracks and subsequent rearward displacement of said burner, said abutment means being also engageable by said surface

upon a pivoting of said burner about said rear roller means with the latter contacting said rear stop means and said formation.

6. The combination defined in claim 5 wherein said abutment means is positioned directly underneath said rear stop means, said surface being part of a bottom edge of said burner coming to rest against said abutment means upon a swinging thereof about either of said roller means.

7. In a generator having an apertured wall for receiving the mouth of an externally positioned burner provided with a bottom appendage, the combination with said burner of a mounting therefor including a pair of brackets adjacent said wall flanking said bottom appendage and two substantially horizontal tracks; front and rear stops rising from each track at locations relatively close to and relatively remote from said wall, respectively; front and rear roller pairs on said burner normally resting on said tracks for stably supporting said burner thereon, said front and rear stops being more widely separated than said front and rear roller pairs and being respectively engageable by the latter in an operative position in which the burner mount projects through said wall and an inoperative position in which the burner mouth is withdrawn from said wall; and a formation on each of said brackets above said tracks overlying only said rear roller pairs in said inoperative position while leaving said front roller means freely movable in an upward direction, thereby enabling pivotal movement of said burner on said rear roller pair upon the latter contacting said rear stops and said formations.

8. In a generator having an apertured wall for receiving the mouth of an externally positioned burner provided with a bottom appendage, the combination with said burner of a mounting therefor including a pair of brackets adjacent said wall flanking said bottom appendage and two substantially horizontal tracks; front and rear stops rising from each track at locations relatively close to and relatively remote from said wall, respectively; front and rear roller pairs on said burner normally resting on said tracks for stably supporting said burner thereon, said front and rear stops being more widely separated than said front and rear roller pairs and being respectively engageable by the latter in an operative position in which the burner mouth

projects through said wall and an inoperative position in which the burner mouth is withdrawn from said wall; a formation on each of said brackets above said tracks overlying only said rear roller pairs in said inoperative position while leaving said front roller means freely movable in an upward direction, thereby enabling pivotal movement of said burner on said rear roller pair upon the latter contacting said rear stops and said formations; and abutment means on said brackets below said track, said burner having lateral bottom edges engageable with said abutment means in at least one limiting position of said pivotal movement.

9. The combination defined in claim 8 wherein each of said stops comprises a hook-shaped projection on each of said brackets, said formation being part of the projection constituting each of said rear stops, said tracks sloping downwardly toward said front stops, thereby tending to maintain said front rollers positively engaged by said front stops.

10. The combination defined in claim 9 wherein said front roller pair are of substantially the same size as said rear roller pair and engageable by said rear stops upon a lifting of said rear roller pair from said tracks and subsequent rearward displacement of said burner, said abutment means being also engageable by said bottom edges upon a pivoting of said burner about said rear roller means with the latter contacting said rear stop means and said formation.
